CLAIM

The ornamental design for a phone case, as shown and described in the Figures.

DESCRIPTION

FIG. 1 is front perspective view of the closed phone case; FIG. 2 is a front perspective view of the phone case opened; FIG. 3 is a front perspective view of the phone case with the inner pouch removed; and, FIG. 4 is a rear perspective view of the closed phone case. The broken lines with long dashes shown on the surface of the claim represent stitching and are part of the claimed design.
